(57) **CLAIM**

The ornamental design for a pet tracking and monitoring device, as shown and described.

DESCRIPTION

FIG. 1 is a front perspective view of the pet tracking and monitoring device in accordance with the disclosed subject matter.

FIG. 2 is a front view of the pet tracking and monitoring device shown in FIG. 1.

FIG. 3 is a rear view of the pet tracking and monitoring device shown in FIG. 1.

FIG. 4 is a right side view of the pet tracking and monitoring device shown in FIG. 1.

FIG. 5 is a left side view of the pet tracking and monitoring device shown in FIG. 1; and,

FIG. 6 is a top view of the pet tracking and monitoring device shown in FIG. 1; and,

FIG. 7 is a bottom view of the pet tracking and monitoring device shown in FIG. 1.

The broken lines illustrate portions of the pet tracking and monitoring device that form no part of the claimed design.
